UNITED STATES PATENT OFFICE.

GEORGE TRUOG, JR., OF CUMBERLAND, MARYLAND, ASSIGNOR TO THE POTOMAC GLASS COMPANY, OF CUMBERLAND, MARYLAND, A CORPORATION OF MARYLAND.

DESIGN FOR A DRINKING VESSEL OR SIMILAR ARTICLE.

44,043.

Specification for Design. Patented May 13, 1913.

Application filed April 10, 1913. Serial No. 760,320. Term of patent 7 years.

To all whom it may concern:

Be it known that I, GEORGE TRUOG, Jr., a citizen of the United States, and residing at Cumberland, in the county of Allegany and State of Maryland, have invented a certain new, original, and ornamental Design for a Drinking Vessel or Similar Article, shown in the accompanying drawing, which is a view in elevation of the same.

I claim:—

The ornamental design for a drinking vessel or similar article, as shown.

GEO. TRUOG, Jr.
